BRACKET ARRANGEMENT FOR SHELVES
OR THE LIKE

Richard Egidius Carlsson, Stockholm, Sweden

Application December 22, 1933, Serial No. 703,614
In Sweden November 22, 1932

5 Claims. (Cl. 248—19)

The present invention relates to an adjustable bracket arrangement for shelves, supporting arms, suspension hooks, work-platforms and the like by means of which it is rendered possible to place 5 the shelves or the like at desired elevations without the necessity of operating spring actuated ratchets or the like or of moving other special position-fixing members. More particularly, the invention relates to a bracket arrangement of 10 this kind comprising a bracket supporting post or upright.

The arrangement according to the invention which is convenient in operation and can be produced at a small cost on account of its simple construction, is characterized substantially therein that the bracket and the post are provided with sleeves adapted for displacement within each other and composed of plates rolled together substantially in the shape of spirals.

20 The invention will be more particularly described with reference to the accompanying drawing wherein preferred embodiments are illustrated by way of example.

Figure 1 shows two plates cut to a shape suitable for forming the sleeves.

Figure 2 shows two sleeve-plates in engagement.

Figure 3 is a cross sectional view of the two sleeves telescoped into each other, and

30 Figure 4 shows a modified embodiment of the sleeves.

In the embodiment illustrated in Figures 1 to 3, the sleeve for the bracket-carrying post or upright is made of a plate 1, Figure 1, which plate 35 at one longitudinal edge 4 thereof is formed with equally spaced recesses or notches 3. The bracket sleeve required for connecting the bracket to the post is made of a rectangular plate 2, said plate being provided at its upper and lower edges with 40 two teeth 5 and 6 which project in opposite directions in order to adapt the sleeve both for a right hand and a left hand post. In Figure 2 is illustrated the engagement between the bracket plate 2 and the post plate 1, the bracket plate being shown in a position corresponding to a loaded bracket.

At its notched edge, the plate piece 1 is bent or rolled together for example to form a spiral or involute as illustrated in Figure 3, the notched edge 4 being bent a full turn. The plate piece 2 is also rolled together to form a spiral or involute and in such a manner, that the edge provided with the teeth 5 and 6 will lie in the same plane as the unbent portion of said piece of plate. The 55 sleeve-shaped portions of the plates 1 and 2 are

dimensioned in such a manner that the bracket sleeve 2 can be inserted or telescoped into the post sleeve 1 and displaced freely up and down.

When loading the bracket the bracket-sleeve 2 will rock in relation to the post sleeve, so that the tooth 6 reaches into one of the notches 3 in the post sleeve. The web plate of the post sleeve as well as the jib portion of the bracket sleeve may be shaped in any suitable manner. The post sleeve may, for example, constitute part of a free standing post or be provided with fixing wings for securing the sleeve to a wall or the like by means of screws. The bracket sleeve may be connected in an arbitrary manner with an arm or hook or for example with a shelf, a platform or the like 15 made in any suitable manner.

In order to prevent lateral turning of the bracket sleeve in cases when only a single post sleeve is used it is preferable to shape the involute or spiral of both the post sleeve and the bracket sleeve with plane side walls which guide each other mutually as shown in Figure 4. For the latter purpose a triangular shape for the section of the sleeves may, of course, be quite sufficient.

25 In the embodiment shown in Figure 4 the plane portion of the plate 2 is arranged in the same plane as the outermost side of the post sleeve, which construction is particularly suitable in show stands, book-shelves and similar arrangements.

The arrangement according to the invention is of particular interest for scaffolds of the kind where it is desired to be able conveniently to shift a work-platform or the like to a required 30 elevation while work is going on.

35 A plurality of modified embodiments according to the invention are possible. Thus, the sleeves may be made with a U-shaped profile or tubular in which latter case the sleeve is provided with a longitudinal slot. The bracket sleeve need not necessarily be provided with projecting teeth but the end edges of the sleeve may serve the same purpose as the teeth. The term "involute" as used in the claims is employed in its generic sense 40 to mean spirals or the like whether the sides are curves, straight lines with right angle bends similar to rectangles, or straight lines with acute angles to give the general appearance of a triangle. When the sleeve is made in the shape of an involute with curved edges the locking means may be released by turning the bracket member or by relieving the weight on the bracket and drawing it as far as permitted directly away from the base which is the method of releasing when 45 50 55

a generally rectangular or triangular sleeve is of said base member and mutual engaging means employed.

I claim:—

1. An adjustable support for shelves, supporting arms and the like comprising a base member provided with a sleeve involute in cross section, a bracket member also provided with a sleeve involute in cross-section telescoping with the sleeve of said base member and means on each member mutually engageable at the centers of the sleeves.
2. An adjustable support for shelves, supporting arms and the like comprising a base member provided with a sleeve involute in cross section, and with notches at the inner edge, a bracket member also provided with a sleeve having teeth at the inner edge, involute in cross-section telescoping with the sleeve of said base member, said teeth and notches cooperating to hold the bracket member in any desired position.
3. An adjustable support for shelves, supporting arms and the like comprising a base member provided with a sleeve which is a one turn involute in cross-section, a bracket member also provided with a sleeve which is a one turn involute in cross-section telescoping with the sleeve
4. An adjustable support for shelves, supporting arms and the like comprising a base member provided with a sleeve which is a one turn involute in cross-section, a bracket member also provided with a sleeve which is a one turn involute in cross-section telescoping with the sleeve of said base member and mutual engaging means on each member operative when the base member and the bracket member are in planes substantially at right angles.
5. An adjustable support for shelves, supporting arms and the like comprising a base member provided with a sleeve which is a one turn involute in cross-section, a bracket member also provided with a sleeve which is a one turn involute in cross-section telescoping with the sleeve of said base member and mutual engaging means on each member operative when the base member and the bracket member are in planes substantially at right angles and slidable when the bracket member and the base member are in planes approaching parallelism.
6. An adjustable support for shelves, supporting arms and the like comprising a base member spirally bent along one edge until that edge extends in the same direction as originally, a bracket member telescoped with the base member by a portion spirally bent along one edge until that edge extends in the same direction as originally, and cooperating means to hold the bracket member and base member in fixed relative positions.

RICHARD EGIDIUS CARLSSON.
